ATTORNEY.

UNITED STATES PATENT OFFICE.

WALTER ANDREW INMAN, OF WAUKEGAN, ILLINOIS.

REFRIGERATOR.

Application filed January 24, 1927. Serial No. 163,160.

The invention relates to refrigerators and more particularly to those employing ice as the refrigerating source.

An object of the invention is to provide 5 an ice-cooled refrigerator of simple and inexpensive construction including an ice-receiving cooling compartment containing a circulatory cooling fluid which permits the maintenance of substantially uniform cooling 10 temperature on large cooling surfaces irrespective of the amount of ice present.

Another object of the invention is to provide a refrigerator including a reserve ice supply by which the ice compartment may 15 be kept filled so as to necessitate only infrequent servicing.

A further object is to provide a refrigerator including a cooling compartment having an extensive air-cooling surface, presenting 20 low resistance to the passage of circulating air.

The invention further consists in the several features hereinafter set forth and more particularly defined by the annexed 25 claims.

In the accompanying drawings

Fig. 1 is a sectional elevation of a refrigerator embodying the invention;

Fig. 2 is a transverse sectional view there- 30 of taken on the line 2—2 of Fig. 1;

Fig. 3 is a detail perspective view of an ice-receiving baffle, and

Fig. 4 is a top plan view of a modified 35 form of refrigerating device.

In these drawings, the numeral 10 designates a refrigerator cabinet including a provision compartment 11 having the usual apertured shelves 12. A vertical baffle 13 separates the provision compartment from 40 a laterally adjacent cooling compartment

14, and the ends of the baffle are spaced from the top and bottom of the provision compartment to permit circulation of air currents between the compartments, as hereinafter described. The cooling compartment 45

14 includes a bottom plate 15 spaced above the bottom wall of the provision compartment and having an air opening 16 surrounded by an upstanding flange 17 to prevent the dripping of water from the cooling compartment into the provision compartment, drainage from the cooling compartment being permitted by an overflow pipe 18 preferably including a trap 19.

55 An elongated sheet metal container 20 is

mounted in upright position within the cooling compartment 14 on suitable supports 21 and in spaced relation to the walls of the compartment to provide surrounding air passages 22. The side walls of the container 60 20 are provided with vertically extending corrugations 23 which offer low resistance to the downward flow of air and may be varied in depth and pitch to obtain the desired cooling area. Within the container 65 20 is mounted a tubular ice-receptacle or baffle 24 spaced inwardly from the side walls of the container 23 to form a surrounding liquid-receiving space 25, as hereinafter described. The ice-receptacle 24 is 70

open at its top and bottom and is provided with long horizontal notches 26 at its lower edge and long horizontal slots 27 near its upper edge to form liquid passages. An ice 75 hopper 28 has its lower end projecting into the ice-receptacle 24 and has its upper end suitably mounted near the top of the refrigerator. For convenience in handling the ice-receptacle and hopper are made separately but, if desired, they may be made 80

integrally or connected. Above the provision compartment 11 is formed a reserve ice compartment 29, the bottom 30 of which forms the upper wall of the provision compartment. The upper end of the baffle 13 is 85 spaced downwardly from the wall 30 to form an upper air passage connecting the provision compartment and cooling compartment. A lid 31 is provided to gain 90 access to the ice hopper and reserve ice chamber, and the usual provision door 32 is mounted in the front wall of the refrigerator for access to the provision compartment. If found desirable to facilitate cleaning other well-insulated doors may also be included. 95

In servicing the refrigerator the ice-receptacle 24 is supplied with broken ice through the hopper 28, sufficient ice being added to fill the hopper. At the same time 100 a reserve supply of ice is placed in the reserve ice compartment 29. Sufficient water is then introduced into the container 25 to fill the container to a level above the slots 27 in the ice-receptacle 24. One or more

overflow openings 33 are formed in the container 20 to determine such level, and any discharge from such openings is conducted through the overflow pipe 18 at the bottom of the cooling compartment. The space 105 25 between the ice-receptacle 24 and the walls 110

of the container 20 will be occupied by water, and the water rises to the same level within the ice-receptacle 24, wherein it occupies the interstices between the broken ice. A thermo-siphon circulation of water will then be set up within the container 20 in the direction indicated by arrows, that is, downwardly within the ice-receptacle 24 between the pieces of broken ice, outwardly 5 near the bottom of the container through the notches 26 of the ice-receptacle, upwardly along the corrugated walls of the container 20, and then inwardly near the upper end of the container through the slots 10 27 in the baffle. In this process the circulating water will assume a temperature approximately that of melting ice (32° F.) and this temperature will be maintained within close limits until almost all the ice 15 within the baffle has been melted. The latter condition, however, will not be reached until after all the ice in the hopper 28 has descended into the ice-receptacle, so that only infrequent replenishing of ice is necessary. In the intervals between icing the broken ice in the reserve compartment 29 is transferred to the hopper, preferably before the ice reaches the bottom of the hopper in order to avoid unnecessary splashing and 20 loss of the ice-cold water from the container 20 through the overflow opening 32. The reserve ice compartment 29 is provided with a drain opening 34 by which water will be prevented from accumulating within the 25 compartment.

In operation, the circulation of ice-cold water within the container 20, as above described, serves to maintain the corrugated walls of the container 20 at a temperature 30 approximately that of the melting ice. A thermo-siphon circulation of air then takes place downwardly along the outside surface of the vertically corrugated container 20, through the opening 16 at the bottom 40 of the cooling compartment across to the provision compartment 11 and upwardly therein, and thence across to the upper portion of the cooling compartment. Since the area of the cooling surface remains constant 45 and at a substantially constant low temperature, the circulatory air currents passing through the cooling and provision compartments will remain at an approximately uniform low temperature to properly refrigerate the contents of the provision compartment. 50

In lieu of the rectangular cooling container 20 and associated ice-receptacle 24, there may be provided a vertically corrugated circular container 20' associated with an inner concentric tubular ice-receptacle 24', as indicated in Fig. 4.

When it is desirable to provide cooling temperatures below that of melting ice, this 60 can be readily accomplished by substituting

brine for water, but the latter liquid is satisfactory in refrigerators intended for domestic use.

If it is found desirable to exclude liquid from the air spaces of the cooling compartment, this can be accomplished by extending the overflow piping to the overflow opening 70 33 and drain opening 34.

The invention provides an ice-cooled refrigerator of relatively simple and inexpensive construction, which provides efficient and uniform refrigeration and requires but infrequent servicing. 75

What I claim as new and desire to secure by Letters Patent is:

1. In a refrigerator, the combination of a liquid-receiving container having heat-conducting walls, and an ice receptacle mounted within said container and providing a surrounding liquid-receiving space between said receptacle and container, said receptacle including side walls imperforate at an intermediate portion and said space communicating with the interior space of said receptacle at regions spaced vertically apart by the imperforate intermediate portion of said side walls to provide a thermo-siphon circulation of liquid downwardly in said ice receptacle and upwardly in said surrounding space to cool the walls of said container. 90

2. In a refrigerator, the combination of a liquid-receiving container having heat-conducting walls, a tubular baffle member within said container including side walls forming an ice compartment therewithin and providing a surrounding liquid-receiving space between said side walls and said container, said side walls having an imperforate intermediate portion and being apertured above and below said imperforate portion to provide for communication of liquid between said ice compartment and liquid-receiving space and to permit a thermo-siphon circulation of cooling liquid downwardly in said ice compartment and upwardly in said surrounding space to maintain the walls of said container at a low temperature. 100

3. In a refrigerator, the combination of a liquid-receiving container having heat-conducting walls, a tubular baffle member within said container forming an ice compartment therewithin and providing a surrounding liquid-receiving space between said baffle member and said container, said baffle member being imperforate except for openings adjacent its lower edge and openings adjacent its upper edge to provide for communication of liquid between said ice compartment and liquid-receiving space and to permit a thermo-siphon circulation of cooling liquid downwardly in said ice compartment and upwardly in said surrounding space to maintain the walls of said container at a low temperature. 110

4. In a refrigerator, the combination of a cabinet having a provision compartment and a cooling compartment communicating to permit thermo-siphon circulation of air upwardly in said provision compartment and downwardly in said cooling compartment, a liquid-receiving container within said cooling compartment having heat-conducting walls along which pass the downwardly moving air currents, a baffle member within said container defining walls of an ice compartment at one side and walls of a liquid-receiving space at the other side, said baffle member having side walls including an imperforate intermediate portion and there being communication between said ice-receiving space and liquid-receiving space at regions spaced vertically by the imperforate intermediate portion of said side walls whereby to establish a thermo-siphon circulation of cooling fluid downwardly in said ice-receiving space and upwardly along the walls of said container to maintain said last-named walls at a low temperature.
5. In a refrigerator, the combination of a cabinet having communicating provision and cooling compartments traversed by circulatory air currents, a liquid-receiving container mounted in said cooling compartment and having vertically corrugated heat-conducting walls spaced from the walls of said compartment to form a surrounding air passage, and a baffle member within said container forming an ice compartment there within and providing a surrounding liquid-receiving space between said baffle member and said container, said space communicating with the interior space of said baffle member only at regions spaced vertically a substantial distance apart to provide a thermo-siphon circulation of liquid downwardly in said ice compartment and upwardly in said liquid-receiving space to cool the walls of said container.
6. In a refrigerator, the combination of a container having heat-conducting walls, and a baffle member within said container forming an ice compartment therewithin and providing a liquid-receiving space between said baffle member and said container, said baffle member being imperforate at an intermediate portion and said space communicating with the interior space of said baffle member at regions spaced vertically apart by the imperforate intermediate portion of said baffle member to provide a thermo-siphon circulation of cooling liquid downwardly in said ice compartment and upwardly in said liquid-receiving space to maintain the walls of said container at a low temperature.
7. In a refrigerator, the combination of a liquid-receiving container having a heat-conducting wall, and a baffle member within said container forming a wall of a refrigerant compartment therewithin and said baffle member forming with said container wall an interposed liquid-receiving space, said baffle member being imperforate at an intermediate portion and said liquid-receiving space communicating with the refrigerant compartment at regions spaced vertically apart by the imperforate intermediate portion of said baffle member to provide a thermo-siphon circulation of cooling liquid downwardly in said refrigerant compartment and upwardly in said liquid-receiving space to maintain the wall of said container at a low temperature.

In testimony whereof I affix my signature.

WALTER ANDREW INMAN.
